UNITED STATES PATENT OFFICE.

WILLIAM N. HUNTER, OF BLANCHESTER, OHIO.

FASTENER.

Application filed February 13, 1925. Serial No. 8,887.

My invention relates to fasteners more particularly for straps or flexible members for handbags, mail bags, pouches and the like, although the fastener can be used for 5 any other purposes for which it is found applicable.

The object of my invention is to provide a simple and effective device for this purpose, which when the two members are brought 10 together and caught will not have any tendency to spring open and in which the latches as they are forced into locking position will draw the two members more closely together so that there will be no looseness 15 or lost motion between the parts, nor any liability to pull apart and in which the latches can be permanently locked with a key.

My objects are attained by that particular 20 combination and arrangement of parts which will be hereinafter more particularly described and set forth in the claims.

In the drawing:

Figure 1 is a front view of the fastener 25 with the two members separated and with the front cover removed.

Figure 2 is a similar view with the two members in locking position.

Figure 3 is a central longitudinal section 30 of the parts as shown in Figure 1.

The straps or other members to be secured together are indicated at 1 and 2. The casing for the locking members is flat and formed of a back plate 7 and a cover 8 for 35 one member and a back plate 9 and cover plate 10 for the other member. Between these members the two parts of the strap are secured by rivets 3, 4, and 5, 6. In each case in order to insure against the straps pulling 40 out in use, the straps are first folded around a thin metal plate 4^a and 5^a in each instance and the folded end is inserted between the front and back plates of the respective casings. Mounted between the front and back 45 plates 7 and 8 at each side are permanently secured hook members 11 and 12 formed with hooks 13 and 14 turned towards each other.

Between the front and back plates of the 50 other member are mounted on the rivet 15, so as to rock, the L-shaped latches 16 and 17. The horizontal arms of these latches project through the sides of the casing which are cut away to allow the latches to turn 55 when pushed upwardly. A spring 18 is mounted between the vertical arms 19, 19,

of the latches to force them outwardly and the outer ends of these arms are formed with hooks 20, 20, extending downwardly in a position to engage the hooks 13, 14, of 60 the other locking member when the latches are inserted between the cover plates 7 and 8. The projecting lower edges of the fixed hook members 11 and 12 are beveled at 21, and the outer edges of the latches are correspondingly beveled so that as the latches are inserted they will be rocked to permit the latches to pass the fixed hook members when the spring 18 will insure engagement 65 of the hooks. The hooks are sloped in their 70 engaging edges in opposite direction so that, as they engage, the casing members of the two parts are drawn towards each other thus taking up any lost motion or looseness 75 between the parts. The respective hooks being thus interlocked there is no liability of the latches slipping out of engagement.

In order to lock the latches in engagement I mount in the upper casing a keeper 22 which can be turned by a key. This keeper 80 has lugs 23 and 24 which when turned anti-clockwise enter between the ends of the latches to hold them in locked position. A head or lug 25 is formed on one of the latch hooks to serve as a stop for the lug on the keeper when in locking position, and a stop 85 26 limits the opening movement in the opposite direction.

As the latches in one member and the hooks in the other are all in the same plane 90 the entire construction can be made very thin so that the two members of the lock will add very little to the thickness of the straps or other parts that are to be locked together and in making engagement the latch hooks swing downwardly so as to pull the parts together and to make a close joint between the ends of the straps.

Having thus described my invention, what I claim as new and desire to secure by Letters Patent, is:—

1. In a fastener of the character specified comprising two casing members, one member provided with a pair of permanently fixed hooks spaced apart and facing each other, and the other member provided with a corresponding pair of L-shaped latches pivoted together, with one arm of the L-shaped latches provided with hooked ends turned in opposite directions to be inserted 105 between the fixed hooks and the other arm projecting from the sides of the casing and 110

a spring to hold the hooked end of the latches separated, the interengaging hooks being beveled to draw the two casing members together upon engagement.

6. 2. In a fastener of the character specified comprising two casing members, one member provided with a pair of permanently fixed hooks spaced apart and facing each other, and the other member provided with

19 a corresponding pair of L-shaped latches

pivoted together, each latch having a hooked end turned so as to engage a permanently fixed hook, and each latch having an arm projecting from the casing, the permanently spaced hooks having beveled engagement portions to cause the hooked ends of the latches to approach, one the other, during insertion, and means tending to resiliently hold the hooked ends of the latches apart.

WILLIAM N. HUNTER.
